CLAIM

The ornamental design for a housing for aerial imaging apparatus, as shown and described.

DESCRIPTION

FIG. 1 is a perspective view of a housing for aerial imaging apparatus showing our new design;

FIG. 2 is a front view thereof;

FIG. 3 is a rear view thereof;

FIG. 4 is a right side view thereof, opposite left side view being mirror image thereof;

FIG. 5 is a top view thereof; and,

FIG. 6 is a bottom view thereof.

In FIGS. 1-6, the broken lines shown in the drawings are for illustrative purposes only and form no part of the claimed design.
